UNITED STATES PATENT OFFICE

2,387,917

INHALER

Joseph A. La Bille, Chicago, Ill.

Original application April 8, 1940, Serial No. 328,555. Divided and this application April 11, 1945, Serial No. 587,669

4 Claims. (Cl. 128—192)

My invention, in its broad aspect, has reference to improvements in devices for applying heated moistened medicament to the afflicted parts in nasobronchial disorders, and an inhaler is associated with a novel heating and moistening device for air whereby suitable medicament in the inhaler is mixed with the moistened and heated air and the vapors drawn into the nasal and bronchial passages by the respiratory action of the person being treated. My present application is a division of my allowed application, Serial #328,555, filed April 8, 1940, on Inhalers.

In attaining the objects and advantages of my invention, I provide a container for water, or the like, mounted on a base in which is an electric heating or resistance element. Mounted on the container is a coil having one end turned to extend vertically through the top of the container. The extended end of the coil has a cup-shaped formation to receive a moisture saturated sponge, and openings are formed in the top of the container so that moist vapor rises from the heated water in the container about the sponge. The opposite end of the coil extends out from the container and has attached thereto an improved inhaler, in which medicament is placed so that the person using the inhaler will draw the heated, moist air from the coil, the sponge, and the connection with the tube to mix the medicament with the same to treat the afflicted parts. My device is sturdy, simple, practical, and easily operated and cleaned and kept in first-class condition.

Other and equally important objects and advantages of my invention will be apparent from the following description and drawing, and it is pointed out that changes in form, size, shape, materials and construction and arrangement of parts is permissible and within the purview of my broad inventive concept and the scope of the appended claims.

In the drawing, wherein I have illustrated a preferred form of my invention:

Figure 1 is a side view of my device, partly in section, and

Figure 2 is a longitudinal section through the inhaler per se.

In the drawing, wherein like characters of reference are used to designate like or similar parts throughout the several views:

The numeral 1 designates a cylindrical container having a back 2 with legs 3 and an electric connection 4 leading to a heating coil or resistance coil in the base (not shown) in heat transferring relationship to water 5 or the like in the container. The container has a top 6 which has

openings 7 through which moist heated vapors rise from the heated water in the container.

5 Mounted in the container is a vertical coil 8, the lower end of which is turned to rise vertically as at 9 through the center of the coil and out the top 6 of the container. A cup-shaped formation 10 is carried or formed on the end of the vertical extension 9 in which is disposed a water saturated sponge 11, or the like, and it will be noted that the moist vapors from the water within the container also contact the sponge.

15 The upper and remaining end 12 of the coil passes out of the top of the container through a bored boss 13. Connected with the end 12 is an inhaler having a cylindrical hollow body 14 and a counter bore 15 forming an annular shoulder 16, on which is seated a circular foraminated disk 17 having a pin 18 on which medicament 19 is removably placed. The opposite end of the body is closed by a suitable nipple 20 formed of rubber or the like from which the vapors are drawn through the inhaler and in contact with the medicament 19 to form a curative mixture which reaches the afflicted parts through the 20 respiratory action of the user. The disk is readily removable from the inhaler.

25 In operation, the air passing through the saturated sponge 11, about which water vapors also pass, is heated in the coil and passes to the inhaler where it is mixed with the medicament 19 carried by the pin 18 on the disk.

30 From the foregoing, it is believed that the operation and advantages of my invention will be apparent, but it is again emphasized that interpretation of the scope of my invention should only be conclusive when made in the light of the subjoined claims.

I claim:

35 1. A device for producing heated, moistened medicament for nasobronchial disorders, comprising a container for water having a base, a heating element in the base, the top of the container having openings, a coil in the container having its lower end turned and rising vertically through the top of the container, a cup-like formation at the top of the vertical end, water saturated material in the cup-like formation, the other end of the coil extending out of the container, an inhaler on the latter end, and medicament in the inhaler to contact and mix with the moistened heated air.

40 2. A device for producing heated, moistened medicament for nasobronchial disorders, comprising a medicament supporting device having air passages about the medicament to enable a

patient to draw air over and around the medicament, an air heating and moistening device, including a container for heating water and material to absorb water, and an air tube connected with the medicament supporting device, and formed with means for supporting the material for absorbing water at the other end, the tube coiled between its ends and the coil located in the heating device, and said heating device located in proximity with the material to absorb water and having hot water therein.

3. The device as defined in claim 1 wherein the

container is cylindrical, and the coil is vertically arranged, and the end of the coil having the cup-shaped support rising vertically and centrally of the coil and extending through the top of the container.

4. The invention as defined in claim 1, wherein the inhaler has a cylindrical, hollow-body connected with the tube and having a nipple at its other end, and a removable medicament support in the body including a foraminated circular base and a pin on which the medicament is placed.

JOSEPH A. LA BILLE.
